CLAIM

The ornamental design for a cleaning trolley, as shown and described.

DESCRIPTION

FIG. 1 is a perspective view of a cleaning trolley constructed according to the principles of the present invention;

FIG. 2 is a side view of the cleaning trolley shown in FIG. 1, the other side is a mirror image thereof;

FIG. 3 is a top view of the cleaning trolley shown in FIG. 1; FIG. 4 is a bottom view of the cleaning trolley shown in FIG. 1;

FIG. 5 is a front view of the cleaning trolley shown in FIG. 1; and,

FIG. 6 is a rear view of the cleaning trolley shown in FIG. 1.

The broken line showing of some elements in the figures is included for the purpose of illustrating environment and forms no part of the claimed design.

1 Claim, 6 Drawing Sheets

UNITED STATES PATENT AND TRADEMARK OFFICE
CERTIFICATE OF CORRECTION

PATENT NO. : Des. 624,271 S

Page 1 of 1

APPLICATION NO. : 29/346615

DATED : September 21, 2010

INVENTOR(S) : Stephan Uhl et al.

It is certified that error appears in the above-identified patent and that said Letters Patent is hereby corrected as shown below:

Page 2, 2nd column, last line:

“Mar. 18, 2010.” should read --Mar. 8, 2010.--

Signed and Sealed this

Seventh Day of December, 2010

David J. Kappos
Director of the United States Patent and Trademark Office
